UNITED STATES PATENT OFFICE

WALDEMAR KOPS, OF NEW YORK, N. Y., ASSIGNOR TO KOPS BROTHERS, INC., OF NEW YORK, N. Y., A CORPORATION OF NEW YORK

DESIGN FOR A BOX OR SIMILAR CONTAINER

Application filed March 4, 1932. Serial No. 43,073. Term of patent 14 years.

To all whom it may concern:

Be it known that I, WALDEMAR KOPS, a citizen of the United States, residing at New York, in the county and State of New York, have invented a new, original, and ornamental Design for Box or Similar Container, of which the following is a specification, reference being had to the accompanying drawing, forming a part thereof.

The figure illustrates in perspective a container embodying my new design.

I claim:

The ornamental design for a box or similar container, as shown.

WALDEMAR KOPS.
